[57] CLAIM

The ornamental design for an automated machine for delivering and receiving dry cleaning and laundry, as shown and described.

DESCRIPTION

FIG. 1 is a perspective view of an automated machine for delivering and receiving dry cleaning and laundry, showing my new design;

FIG. 2 is a right side elevational view thereof;

FIG. 3 is a rear elevational view thereof;

FIG. 4 is a front elevational view thereof;

FIG. 5 is a top plan view thereof; and

FIG. 6 is a fragmentary perspective view thereof, showing an extendedly enlarged control panel.
